(57) **CLAIM**

I claim the ornamental design for the combination brush and tape roller, as shown and described.

DESCRIPTION

FIG. 1 is a perspective view of the invention with the handle in the closed position, showing my new design;

FIG. 2 is a top plan view thereof;

FIG. 3 is a bottom plan view thereof;

FIG. 4 is a side elevational view thereof; the opposite side being a mirror image;

FIG. 5 is a front end view thereof;

FIG. 6 is a rear end view thereof;

FIG. 7 is a perspective view of the invention with the handle in the open position;

FIG. 8 is a top plan view thereof;

FIG. 9 is a bottom plan view thereof;

FIG. 10 is a side elevational view thereof; the opposite side being a mirror image;

FIG. 11 is a front end view thereof; and,

FIG. 12 is a rear end view thereof.
